US00D555878S

(12) **United States Design Patent** (10) Patent No.: **US D555,878 S**
Bay (45) Date of Patent: **** Nov. 27, 2007**

(54) **RECONFIGURABLE MOTORCYCLE JACKET**

(75) Inventor: **Marc A. Bay**, Farmington, MI (US)

(73) Assignee: **Robison's Inc.**, Idaho Falls, ID (US)

(**) Term: **14 Years**

(21) Appl. No.: **29/286,443**

(22) Filed: **May 4, 2007**

(51) **LOC (8) Cl. 02-02**

(52) **U.S. Cl. D2/828; D2/830**

(58) **Field of Classification Search .... D2/828, D2/830, 836, 839; 2/59, 86, 93, 95-97, 101, 2/126, DIG. 1**

See application file for complete search history.

(57) **CLAIM**

I claim the ornamental design for a reconfigurable motorcycle jacket, as shown and described.

DESCRIPTION

FIG. 1 is a front elevational view of a jacket showing removable outer shells attached to a jacket body in an assembled configuration of my new design;

FIG. 2 is a rear elevational view of the jacket showing the removable outer shells attached to the jacket body in the assembled configuration of my new design;

FIG. 3 is a top plan view of the jacket showing the removable outer shells attached to the jacket body in the assembled configuration of my new design.

FIG. 4 is an exploded front elevational view showing the removable outer shells detached from the jacket body in a disassembled configuration, exposing the open mesh of the jacket body of my new design; and,

FIG. 5 is an exploded rear elevational view showing the removable outer shells detached from the jacket body in a disassembled configuration, exposing the open mesh of the jacket body of my new design.

The broken line illustration symbolizing stitching as well as the remainder of the broken lines on the surface of the jacket, illustrate portions of the design that form no part of the claim. The partial mesh samples shown along the lower torso segment and lower sleeve segments indicate a continuous open mesh pattern between the partial mesh samples illustrated.

1 Claim, 5 Drawing Sheets
